GARMENT STEAMER

Carl R. Lendle, Youngstown, Ohio

Application February 6, 1942, Serial No. 429,831

10 Claims. (Cl. 223—70)

My invention relates to garments, and has among its objects and advantages the provision of an improved garment renovating and cleaning device of the steam type.

In the accompanying drawings:

Figure 1 is a vertical sectional view in accordance with my invention;

Figure 2 is a sectional detail view of a garment clamp;

Figure 3 is a sectional detail view of the clamp 10 of Figure 2 but showing the clamp in its non-clamping position;

Figure 4 is a sectional detail view of the mount for one of the garment shoulder supports;

Figure 5 is a view taken along the line 5—5 15 of Figure 1;

Figure 6 is a side elevational view of the device;

Figure 7 is a cross sectional view of the upper part of the device illustrating a garment in a 20 steaming position;

Figure 8 is a sectional view along the line 8—8 of Figure 1;

Figure 9 is a sectional detail view of one of the mechanical pressure devices; and

Figure 10 is an elevational sectional view of a housing which may be provided for the device of Figures 1 and 6.

In the embodiment selected for illustration, I make use of base structure 12 comprising an upright tubular shell 14 provided with a reinforcing ring 16 about its lower end. Housing 12 is provided with a series of screened openings 17 for the inlet of air circulated through and about the garment.

Upon the housing 12 is mounted a plate 18 having a downwardly extending flange 20 loosely encircling the upper end of the housing and resting on a flange 22 secured to the housing. Plate 18 may be oscillated a limited distance about the axis of the housing 12. Plate 18 is in the nature of a large disk having a central flange 24 loosely engaging an annular flange 26 on a plate 28 provided with openings 30 for the passage of air. Plate 28 declines centrally and is provided with a depending flange 32 secured to a flange 34 secured to a steam chest 36 arranged coaxially of the housing 12. Steam chest 36 is mounted on supports 38 secured to the housing 12.

A damper plate 40 is mounted on the plate 38 and is provided with a series of openings 42 which may be brought into variable degrees of registration with the openings 30 through rotation of the plate 40. Thus the plate 40 may be adjusted to control the circulation of air through 50 55

the openings 30. A handle 44 is attached to the plate 40 to facilitate rotation thereof.

To the flange 24 is secured an upright and hollow garment form 46, which form comprises 5 a lower section 48 and an upper section 50. The sections 48 and 50 comprise wire mesh 52 having slots 54 extending substantially throughout their entire vertical lengths. The wire mesh of the section 52 is fixedly secured to the flange 24. A reinforcing ring 56 is secured to the upper end of the mesh 52 of the lower section and a similar ring 58 is secured to the lower end of the mesh 52 of the upper section 50. A hinge connection 60 is provided between the sections 48 and 50 to lend accessibility to the interiors of the two sections. The sections 48 and 50, when arranged end to end, are characterized by a uniform taper upwardly, and the two sections are circular in cross section.

A bar 62 is secured to the ring 56 and is provided with a bearing 64 resting on the curved upper end 66 of a shaft 68 secured to the steam chest 36. A cup 70 is secured to the bar 62 for bracing the shaft 68 to hold the bearings 64 and 66 in position. Shaft 68 carries the greater part of the load of the form 46, while the flange 22 serves largely as a means to prevent rocking of the form upon the shaft.

To the sections 48 and 50 are secured a plurality of pressure bags or pouches 72. One bag is provided for each of the slots 54. All the bags are formed of suitable fabric which permits the passage of steam therethrough. Figure 9 illustrates the manner in which the bags are secured to the wire mesh 52. The bag of Figure 9 is illustrated in cross section and has an open side communicating with the slot 54. Vertical reinforcing bars 74 are secured to the mesh 52 by bolts 76 which extend through outside bars 78 between which and the mesh 52 are secured the margins of the bag 72 about the side opening therein. All the bags are identical in construction and operation.

Garments to be steam treated are placed on the form and steam is admitted therein for treating purposes. The pressure of the steam expands the bags, as in Figure 7, so as to hold the garment 80 in a taut condition. The steam passes through the bags and through the mesh between the bags for passage through the garment. The bags 72 exert uniform pressure to the garment throughout all the areas engaged thereby. In addition, the bags are form-fitting so as to press uniformly against irregular contours in order to hold the garment fully distended.

To accommodate the device to garments which vary considerably in size, the bags 72 are provided with extension folds which may be released to considerably enlarge the bags. In Figure 9, the bag 72 is provided with a slide fastener 82 extending longitudinally of the bag. With the slide fastener 82 closed, as illustrated, the excess material of the bag 72 lies in a fold 84 which distends only upon opening of the fastener 82 and the introduction of steam under pressure in the bag. Longitudinal metallic strips 86 are incorporated in the bag 72. These strips are thin and of such flexibility as to bend easily to the contour of the garment. Their stiffness is such, however, as to lend desirable stability to the bag.

Figure 8 illustrates the collapsed conditions of the bags 72. After steaming, suction is created inside the form 46 for removing steam therefrom, which suction causes the bags 72 to collapse to the positions of Figure 8. The end and side margins of the bag 72 fold inwardly in response to the low pressure condition inside the form, and the strips 86 tend to stabilize the form so as to facilitate neat and orderly folding of the bags under the influence of the low pressure condition.

Two garment shoulder supports 88 are provided at the upper end of the section 50. This end of the section is provided with a neck contour 90 having a reinforcing ring 92 incorporated therein, as in Figure 4. The supports 88 comprise bars 94 having a hinge connection 96 with the ring 92, and pads 98 are secured to the outer ends of the bars. Bolts 100 secure the pads to the bars. The bars may be provided with a series of openings to permit adjustment of the pads longitudinally of the bars to accommodate garments of different sizes. A precise fit is unnecessary since the purpose of the supports is to prevent the garment from dropping downwardly on the form and to hold it in place until the bags 72 are distended. The hinges 96 permit the shoulder supports to be folded for compactness.

Figure C illustrates a front garment clamping bar 102 and a rear clamping bar 104. Clamping bar 102 is pivotally connected at 106 with an arm 108 pivotally connected at 110 with the upper end of an arm 112 pivotally connected at 114 with a supporting bar 116 fixedly secured to the flange 28. A tension spring 118 has one end connected with a pin 120 attached to the bar 112 and its other end attached to the support 116. With the bar 112 positioned in accordance with Figure 6, the spring 118 yieldingly holds the bar in the position shown.

To the upper end of the bar 102 is connected a bar 122, as by a bolt 124. Bar 122 may be disconnected from the bar 102. A link 126 has one end pivotally connected with the bar 122 and its opposite end pivotally connected with a member 128 secured to the neck contour 90. A lapel presser member 130 is secured to the bar 122.

Between the bar 102 and the form 46 may be positioned a garment-engaging plate 132 particularly suitable for suit coats of the singlebreasted type. This plate may be shifted vertically in conformity with the length of the coat. Bar 102 may shift laterally upon distention of the bags 72. Such shifting of the bar 102 causes the bar to elevate slightly as it moves laterally but the spring 118 yieldingly holds the bar against the garment so as to retain the garment in an overlapping condition along its front margins.

The coats of the singlebreasted type are supported in a closed position by reason of the plate 132 and the lapel presser 130. Disconnection of

the bar 102 from the bar 122 permits the bar 112 to be pivoted to the dotted line position of Figure 6. A stop 134 is provided on the support 116 for engaging the bar 112 in its dotted line position. Spring 118 is so arranged as to yieldingly support the bar 112 in its full or dotted line positions by reason of the location of the pivot 114.

Rear clamp 104 is pivoted at 136 to a link 138 pivoted at 140 to a bar 142 secured to the flange 120. Bar 104 may be moved to the dotted line position of Figure 2 and is yieldingly held in either position by a tension spring 144 so arranged as to take positions on opposite sides of the pivot 140 when moved to an operative or inoperative position. Bar 142 is provided with a stop 146 to restrain the link 138 from pivotal movement beyond its dotted line position. Clamp 104 is employed in connection with overcoats and the like wherein there is a slit in the lower end of the garment.

Two garment side clamps 150 are provided. Each clamp 150 comprises an upstanding bar 152 having an arm 154 adjustably mounted at 156 on the plate 18 so that the clamp may be moved toward and away from the form 46 in accordance with the demands of particular garments. A pull chain 158 is attached to each of the arms 154 to facilitate outward adjustment thereof. The two side clamps 150 are identical in construction.

In Figures 2 and 3, the side clamp 150 comprises a resilient strap 160 of slight curvature. A body 162 is attached to the strap 160 and is provided with an opening for the reception of the bar 152. The curvature of the strap 160 is normally less than that of the section 48 in the plane of the two clamps 150. To the body 162 is pivotally connected a rigid member 164 of considerably more curvature than the normal curvature of the strap 160. Strap 160 may be bent into garment-engaging position throughout its entire length by pivoting the member 164 to the position of Figure 2 which causes the strap to bend in conformity with the curvature of the member 164. Such a clamp provides a clamping action which engages the garment gently in that the strap is bent progressively to its garment-engaging curvature.

A pipe 166 communicates with the steam chest 36 for delivering steam thereto. The steam chest 36 is perforated at 168 for delivering steam inside the form 46. A quick opening valve 170 is interposed in the pipe 166 and this pipe communicates with the upper end of a chamber 172 having a steam inlet pipe 174 communicating therewith at its upper end. Pipe 174 leads to a suitable steam generator (not shown). A drain pipe 176 has communication with the bottom end of the chamber 172 for removing any condensate which may be collected therein.

An endless pipe 178 is positioned underneath the plate 28 and has communication with the steam pipe 166 through the medium of a branch pipe 180. Pipe 178 is arranged concentrically of the steam chest 36 and is of such diameter as to span the slots 38, as illustrated in Figure 5. The pipe 178 is perforated at 182 to deliver steam through the slots 38 and the openings 42 in the damper plate 40.

Upon the supports 38 is mounted a finned coil 184 having a steam inlet pipe 186 communicating with its inside convolution and an outlet pipe 188 communicating with its outside convolution and the drain pipe 176. The plate 18 is perforated at 180, and the finned coil 184 underlies the plate 18 and the plate 28 so that heated air may circu-

late upwardly of the form 46 inside and outside the latter. A fan 192 is located underneath the finned coil 184 for rotation about a vertical axis to circulate air upwardly through the finned coil. The fan 192 may be driven by a motor 194 mounted inside the base structure 12. Pipe 186 communicates with a pipe 196 leading to the steam generator.

Inside the section 48 of the form 46 is located a heating coil 198 provided with a steam inlet pipe 200 communicating with the pipe 196. A valve 202 is interposed in the pipe 196 to control the admission of steam to the heating coil 198. The outlet pipe 204 of the heating coil 198 has communication with the drain pipe 176. After steaming a garment, steam may be evacuated from the form 46 through the medium of a pipe 206 communicating with the steam chest 38. Pipe 206 communicates with a suitable suction device (not shown).

To the flange 20 is fixedly secured two vertically spaced bars 208 through the medium of supports 210. The two bars 208 are curved in conformity with the flange 20 but are spaced therefrom so that rings 212 secured to the support 116 may slide freely on the bars. Thus the form 46 may be rotated about the axis of the shaft 68 and the clamping bar 102 may be rotated about the axis of the form. Such rotation is desirable when accommodating the form to garments of double-breasted and singlebreasted types. Thus the clamps may be adjusted to bring a particular type of garment into proper relationship with the clamps. Upstanding handles 214 are secured to the plate 18 to facilitate rotation of the form 46.

The valve 202 may be closed to cut off the steam supply with respect to the finned coil 184 and the heating coil 198. Cold air may then be blown into the form 46 for expanding fur coats and the like to shape the garment while a hand nozzle is employed to work the fur from the outside. With the valve 202 open, steam is admitted to both the finned coil 184 and the heater 198 so that heated air may be blown into the form 46. The fan 192 blows air inside the form to expand the bags 72 against the garment. The admission of steam to the form 46 is controlled by the valve 176, and the bag 72 and the mesh 52 are sufficiently pervious to pass steam therethrough for garment-treating purposes.

After steaming a garment, the steam is shut off and the fan 192 is permitted to operate. Thus the air circulated upwardly by the fan 192 is effectively heated by reason of the finned coil 184 and the coil 198 so that the garment may be thoroughly dried while in an expanded condition.

Figure 10 illustrates a casing 216 secured to the base structure 12 and provided with a large opening 218 which may be closed by a door 220. Flanges 222 are attached to the casing 216 for coaction with rollers 224 secured to the door 220. Casing 216 is of sufficient diameter to provide ample space therein for the form 46. The casing may be provided with an opening 226 at its upper end for the circulation of air and steam therethrough by a fan 228.

Two of the bags 72 are provided with sleeve formers 230 of the same material as the bags to form the sleeves and shoulder areas of the garment in cases where such forming is desired.

Without further elaboration, the foregoing will so fully illustrate my invention, that others may, by applying current knowledge, readily adapt the same for use under various conditions of service. 75

I claim:

1. A garment steamer comprising a hollow form, steam pervious garment stretching bag means having communication with the interior of said hollow form, means for admitting steam to said hollow form for passage through said bag means and through a garment draped on the hollow form, said bag means comprising a plurality of bag units spaced about said hollow form, and said hollow form being pervious to steam throughout the spaces between said bag units.
2. A garment steamer comprising a hollow garment form, air pervious garment stretching bag means having communication with the interior of said hollow form, means for blowing heated air into said hollow form for passage through said bag means and through a garment draped on said hollow form to dry the garment, said bag means comprising a plurality of bag units spaced about said hollow form, and said hollow form being pervious to steam throughout the spaces between said bag units.
3. A garment steamer comprising a hollow garment form, air and steam pervious garment stretching bag means having communication with the interior of said hollow form, means for admitting steam to said hollow form for passage through said bag means and through a garment draped on the hollow form, means for blowing heated air into said hollow form to expand said bag means and stretch the garment and pass drying air through the garment, said bag means comprising a series of bag units spaced about said hollow form, and said hollow form being pervious to air and steam throughout the spaces between said bag units.
4. A garment steamer comprising a hollow form, steam pervious garment stretching bag means having communication with the interior of said hollow form, means for admitting steam to said hollow form for passage through said bag means and through a garment draped on the hollow form, said bag means comprising a plurality of bag units spaced about said hollow form, said hollow form being pervious to steam throughout the spaces between said bag units, said hollow form having a lower end provided with openings, and means for variably closing said openings to control the passage of steam therethrough.
5. A garment steamer comprising a hollow garment form, air pervious garment stretching bag means having communication with the interior of said hollow form, means for blowing heated air into said hollow form for passage through said bag means and through a garment draped on said hollow form to dry the garment, said bag means comprising a plurality of bag units spaced about said hollow form, said hollow form being pervious to air throughout the spaces between said bag units, said hollow form having a wall at its lower end provided with a plurality of openings, and means coacting with said wall to variably close said openings for controlling the passage of air therethrough.
6. A garment steamer comprising a hollow garment form, air and steam pervious garment stretching bag means having communication with the interior of said hollow form, means for admitting steam to said hollow form for passage through said bag means and through a garment draped on the hollow form, means for blowing heated air into said hollow form to expand said bag means and stretch the garment and pass drying air through the garment, said bag means comprising a series of bag units spaced about

said hollow form, said hollow form being pervious to air and steam throughout the spaces between said bag units, and means at the lower end of said hollow form for controlling the passage of steam and drying air into the form.

7. A garment steamer comprising a hollow form, steam pervious garment stretching bag means having communication with the interior of said hollow form, means for admitting steam to said hollow form for passage through said bag means and through a garment draped on the hollow form, said bag means comprising a plurality of bag units spaced about said hollow form, said hollow form being pervious to steam throughout the spaces between said bag units, and clamp devices for clamping the garment against the hollow form.

8. A garment steamer comprising a hollow garment form, air pervious garment stretching bag means having communication with the interior of said hollow form, means for blowing heated air into said hollow form for passage through said bag means and through a garment draped on said hollow form to dry the garment, said bag means comprising a plurality of bag units spaced about said hollow form, said hollow form being pervious to air throughout the spaces between said bag units, and clamp devices for clamping the garment against certain of said bag units.

9. A garment steamer comprising a hollow garment form, air and steam pervious garment stretching bag means having communication with the interior of said hollow form, means for admitting steam to said hollow form for passage through said bag means and through a garment draped on the hollow form, means for blowing heated air into said hollow form to expand said bag means and stretch the garment and pass

drying air through the garment, said bag means comprising a series of bag units spaced about said hollow form, air and steam pervious sleeve formers on certain of said bag means, said hollow form being pervious to air and steam throughout the spaces between said bag units, and clamp devices for clamping the garment against said hollow form, said hollow form being rotatable about a vertical axis relatively to said clamp devices and certain of said clamp devices having resilient garment-engaging means and being rotatable about the axis of the form.

10. A garment steamer comprising a hollow garment form, air and steam pervious garment stretching bag means having communication with the interior of said hollow form, means for admitting steam to said hollow form for passage through said bag means and through a garment draped on the hollow form, means for blowing heated air into said hollow form to expand said bag means and stretch the garment and pass drying air through the garment, said hollow form comprising two wire mesh sections hingedly connected together one above the other, said wire mesh being provided with openings in both sections, said bag means comprising a plurality of bag units connected with each section and having openings registering with said first-mentioned openings, said second-mentioned means including a steam chamber communicating with said hollow form, a suction pipe having communication with said steam chamber, said hollow form being provided with a base having a perforated wall for the passage of steam and drying air exteriorly of the garment closely adjacent the hollow form, and means for enlarging said bag units.

CARL R. LENDLE.
